UNITED STATES PATENT OFFICE

KINGSTON FORBES, OF FLINT, MICHIGAN, ASSIGNOR TO GENERAL MOTORS CORPORATION, OF DETROIT, MICHIGAN, A CORPORATION OF DELAWARE

DESIGN FOR A RADIATOR SHUTTER

Application filed November 4, 1931. Serial No. 41,626. Term of patent 3½ years.

To all whom it may concern:

Be it known that I, KINGSTON FORBES, a citizen of the United States, residing at Flint, in the county of Genesee and State of Michigan, have invented a new, original, and ornamental Design for Radiator Shutters, of which the following is a specification, reference being made to the accompanying drawings, forming part thereof.

In the drawings:

Figure 1 is a front elevational view of the shutter with the operative portion thereof in closed position.

Figure 2 is a front elevational view of the shutter with the operative portion thereof in open position.

Figure 3 is an enlarged fragmentary cross section taken on the line 3—3 of Figure 1 and showing the contour of the operative portion of the shutter.

Figure 4 is a view showing the outline of the shutter in side elevation.

A dominant feature of my design is the contrasting effect of alternate light and dark vertical bands. In Figure 1, the vertical beads *a* form relatively narrow light bands and the vertical beads *b* form relatively wide dark bands. In Figure 2, the vertical beads *a* form the relatively narrow light bands, the vertical beads *b* form the portions of the relatively wide dark bands above and below the operative portion of the shutter and the dark background forms the portions of the relatively wide dark bands between the beads *a* in the operative portion of the shutter.

I claim:

The ornamental design for a radiator shutter substantially as shown and described.

KINGSTON FORBES.
